UNITED STATES PATENT OFFICE

HYMAN TAUBER, OF EAST LIVERPOOL, OHIO

DESIGN FOR A LIGHTING FIXTURE

Application filed January 31, 1930. Serial No 34,364. Term of patent 7 years.

To all whom it may concern:

Be it known that I, HYMAN TAUBER, a citizen of the United States, residing at East Liverpool, in the county of Columbiana and State of Ohio, have invented a certain new, original, and ornamental Design for Lighting Fixtures, of which the following is a specification, reference being had to the accompanying drawings, forming a part hereof.

I claim:

The ornamental design for a lighting fixture as shown.

In testimony whereof, I have hereunto subscribed my name.

HYMAN TAUBER.
